(57) **CLAIM**

The ornamental design for an antenna, as shown and described.

DESCRIPTION

FIG. 1 is a top plan view of the first embodiment of an antenna, showing our new design;

FIG. 2 is a front elevation view thereof;

FIG. 3 is a bottom plan view thereof;

FIG. 4 is a top perspective view thereof;

FIG. 5 is a top plan view thereof, with the unclaimed environment not shown;

FIG. 6 is a front elevation view thereof, with the unclaimed environment not shown;

FIG. 7 is a top plan view of the second embodiment of an antenna, showing our new design;

FIG. 8 is a front elevation view thereof;

FIG. 9 is a bottom plan view thereof;

FIG. 10 is a top perspective view thereof;

FIG. 11 is a top plan view thereof, with the unclaimed environment not shown; and,

FIG. 12 is a front elevation view thereof, with the unclaimed environment not shown.

The broken lines show unclaimed environment only and form no part of the claimed design.

1 Claim, 6 Drawing Sheets
